UNITED STATES PATENT OFFICE.

RICHARD H. MARTIN, OF TOCCOA, GEORGIA.

QUICK PLUG ATTACHMENT.

1,273,896.

Specification of Letters Patent. Patented July 30, 1918.

Application filed February 19, 1918. Serial No. 218,124.

To all whom it may concern:

Be it known that I, RICHARD H. MARTIN, a citizen of the United States, residing at Toccoa, in the county of Stephens and State 5 of Georgia, have invented a new and useful Quick Plug Attachment, of which the following is a specification.

The subject of this invention is a quick attachment plug for connecting hose to a 10 hydrant, and the objects of the invention are first, to provide a novel and efficient coupling, second, to provide a hydrant discharge and a quick coupling attachment co-operating therewith, third, to provide a 15 quick coupling with an inner sleeve which forms a water tight joint, fourth, to provide means for removing and replacing any one of the gripping elements, fifth, to provide means for releasing the gripping elements to uncouple the parts, sixth, to provide a cover for one of the coupling members.

With the foregoing and other objects in view, which will appear as the description 25 proceeds, the invention resides in the combination and arrangement of parts and in the details of construction hereinafter described and claimed, it being understood that changes in the precise embodiment of 30 the invention herein disclosed, can be made within the scope of what is claimed without departing from the spirit of the invention.

A practical embodiment of the invention is shown in the accompanying drawing, 35 wherein:—

Figure 1 is a longitudinal sectional view of the device indicated as attached to a hydrant.

Fig. 2 is an end elevation of the attaching 40 plug.

Referring to the drawing by numerals of reference:—

The usual fire hydrant is indicated at 1 and is provided with the ordinary discharge 45 nipple 2 to which a hose may be attached.

Threaded on the nipple 2 is a cylindrical member 3 formed with an interior annular groove 4 adjacent its outer end. The outer end of the casing 3 is reamed to provide the 50 beveled edge indicated at 5, Fig. 1. An annular shoulder 6 is formed in the casing 3 and serves as a seat for a nipple 7 which is formed of soft rubber or like material. As

will be seen these parts are so formed that an even opening is maintained which presents no obstruction to the outflowing water.

Spaced lugs 8 rise from the casing and between these lugs is pivotally secured a curved tongue 9 which extends rearwardly 60 and downwardly from a frusto-conical cap 10. The edges or faces of the pivoted end of the tongue 9 are formed with curved indentations 11 which are adapted to receive the curved portion 12 of a spring 13 which 65 is secured to the member 3 by screws or otherwise. As will be understood, the spring 13 yieldingly holds the cap 10 in any of three positions, this holding effort being assisted or increased by the depressions in 70 which the curved portion 12 of the spring seats.

The part just described forms one element or member of a coupling, the companion member of which is about to be described, which though shown and described as attached to a hydrant is to be understood as attachable to any member designed to be coupled to another member.

The companion member of the coupling 75 consists of a cylindrical casing 14 counter-bored and threaded at one end as seen at 15. Longitudinal slots 16 are formed in the casing 14 and open at the opposite end thereof.

These slots may be of any desired number 80 but are here shown as four. A resilient latch bar 17 is placed in each slot 16 and is held in place by a machine screw 18. The extending end of each latch bar 17 is formed to present a hook or latch member 19, as 85 shown which is adapted to ride over the beveled edge 5 and drop into the annular groove 4 in the usual and well known manner. The member 14 is preferably reamed out to present an inclined face as shown at 90 20 to receive and form a suitable rest for the rubber nipple 7.

A ring 21, of substantially T shape in cross section engages the attaching end of the member 14 to which it is secured by 100 screws 22 which pass through slots 23 formed in the ring 20. This connection allows the ring to be oscillated back and forth. The ring is formed with a series of cam faces 24 which contact the resilient latch bars 17, and when the ring is turned clockwise as viewed 105

in Fig. 2, draw the bars inwardly and release the coupling.

Having thus described the invention, what is claimed as new and sought by Letters Patent, is:—

- 5 1. A quick coupling, comprising a tubular member provided with an annular groove, a shoulder formed in said member, a flexible nipple resting against the shoulder, a second 10 tubular member coöperating with the first member, said second member provided with longitudinal slots, resilient latches held in the slots with their hooked ends projecting from the member, and means for drawing 15 the latches to releasing position.
- 10 2. A quick coupling, comprising a tubular member provided with an annular groove, an annular shoulder formed in said member, a flexible nipple resting against the shoulder 20 and extending from the member, a second tubular member coöperating with the first member, said second member provided with longitudinal slots, resilient latches in said slots, the hooked ends of the latches extending 25 from said latter member, a ring secured to the member, and cam faces on the ring and contacting the latches to draw the latches to unlatched position when the ring is revolved in one direction.
- 15 3. A quick coupling, comprising a tubular member provided with an annular groove, an annular shoulder formed in said member, a flexible nipple resting against the shoulder, a yieldingly held cap pivotally secured to 30 the member, a second tubular member coöperating with the first member, and resilient latches secured to said second member

and adapted to engage the annular groove to lock the members together.

4. A quick coupling, comprising a tubular member provided with an annular groove formed interiorly thereof, a shoulder formed in said member, a flexible nipple resting against the shoulder, a second tubular member coöperating with the first member, and resilient latches secured to said second member and adapted to engage the annular groove to lock the members together.

5. A quick coupling, comprising a tubular member provided with an annular groove formed interiorly thereof, a shoulder formed in said member, a flexible nipple resting against the shoulder, a second tubular member coöperating with the first member, latches secured to said second member and adapted to engage the annular groove to lock the members together, and means for releasing the latches from the groove.

6. A quick coupling, comprising a tubular member, a shoulder formed in said member, a flexible nipple resting against the shoulder, a second tubular member coöperating with the first member, latches secured within the second member and engageable with the first member to lock the members together, and means for releasing the latches.

In testimony that I claim the foregoing as my own I have hereto affixed my signature in the presence of two witnesses.

RICHARD H. MARTIN.
